Joseph A. Read, assor. to
John H. Cahill, of Philadelphia, Pa.
Letters Patent N°. 792, Dated May 13th 1856.

The schedule referred to in these Letters Patent, and making
part of the same.

J

Des.

7932

To all whom it may concern:

Be it known that I, Joseph A. Read, of the City of Philadelphia, and State of Pennsylvania, have invented a new and original ornamental design for the panels of oven, range or stove doors, and I do hereby declare that the following is a full and exact description of the same - reference being had to the accompanying drawings, making a part of this specification, and to the letters of reference marked thereon.

The drawings represent a front elevation of a range with elevated double side oven, the panels of the doors thereof, being ornamented with the design referred to - A, A', being the upper oven doors; B, B', the lower oven doors; C, C', the feed doors; D, the fall door; and E, E', the ash pit doors. The ornamental figures shown on the panels are cast with the respective doors, so as to produce basso-relievo, or raised figures upon the flat panels thereof respectively as shown by a a', b b', c c', d, and e e'.

What I claim as my invention and desire to secure by letters patent, are the figures a a', b b', c c', d, and e e', cast respectively upon the panels of the doors of ovens, ranges, or stoves, substantially as set forth and described, as a new ornamental design for the same.
